ADJUSTABLE APPLIANCE STAND

Viktor Schreckengost, Cleveland Heights, Ohio, assignor
to The Murray Ohio Manufacturing Co., Nashville,
Tenn., a corporation of Ohio

Filed July 1, 1965, Ser. No. 85,980

Term of patent 3½ years

(Cl. D62—4)

Fig. 1

Fig. 2

The fan shown in phantom lines is included for illustrative purposes only.

I claim:

The ornamental design for an adjustable appliance stand, substantially as shown and described.
